DESIGN FOR A DRAFTING INSTRUMENT

Owen D. Premo, Muskegon Heights, Mich.

Application November 5, 1945, Serial No. 123,487

Term of patent 14 years

(Cl. D52—1)

To all whom it may concern:

Be it known that I, Owen D. Premo, a citizen of the United States, residing at Muskegon Heights, in the county of Muskegon and State of Michigan, have invented a new, original, and ornamental Design for a Drafting Instrument, of which the following is a specification, reference being had thereto in the accompanying drawing, forming a part thereof.

The figure is a plan view of a drafting instrument, showing my new design. The instrument is of conventional thickness.

I claim:

The ornamental design for a drafting instrument, substantially as shown and described.

OWEN D. PREMO.
